(57) CLAIM

The ornamental design for a hanging fireplace as shown and described.

DESCRIPTION

FIG. 1 is a top, front and left side perspective view of a hanging fireplace showing my new design;

FIG. 2 is another top, front and left side perspective view thereof;

FIG. 3 is a bottom, front and left side perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof; and,

FIG. 9 is a bottom plan view thereof.

The broken lines in FIGS. 1, 2, 3 and 8 illustrate portions of the hanging fireplace which form no part of the claimed design.
